UNITED STATES PATENT OFFICE.

WILLIAM S. WITTER, OF TOLEDO, IOWA.

SPARK-PLUG TESTER.

1,184,402.

Specification of Letters Patent.

Patented May 23, 1916.

Application filed November 28, 1914. Serial No. 874,567.

To all whom it may concern:

Be it known that I, WILLIAM S. WITTER, a citizen of the United States, residing at Toledo, in the county of Tama and State of Iowa, have invented certain new and useful Improvements in Spark-Plug Testers, of which the following is a specification, reference being had to the accompanying drawings.

10 My invention relates to means for testing spark plugs, and particularly to a device which is so constructed that it may be readily applied to the spark plug to be tested, and will show whether the spark plug is in good 15 working order by permitting a spark to pass between the electrodes of the tester.

The main object of my invention is the provision of a very simple, easily handled and effective tester wherein a single conductor is used for the purpose of conducting the current from the one terminal of the spark plug to the electrodes disposed within the tester, no return circuit being used or necessary.

25 A further object of the invention is to provide a spark plug tester wherein the electrodes of the tester are inclosed within an opaque tube of nonconducting material and wherein a magnifying glass is so disposed 30 that when the tube is held to the eye the spark jumping between the electrodes will be plainly visible.

A further object of the invention is the provision of a tester so constructed that a 35 flexible conductor is provided normally contained within the tester, but adapted to be withdrawn therefrom and applied to the spark plug while the tester itself is held in such position that its spark may be readily observable.

40 A further object is to provide means in a tester whereby the length of the testing spark may be adjusted by adjusting the distance between the electrodes.

45 Further objects will appear in the course of the following description.

My invention is illustrated in the accompanying drawings, wherein—

Figure 1 is a longitudinal diametrical 50 section of a spark plug tester constructed in accordance with my invention; Fig. 2 is a section on the line 2—2 of Fig. 1; Fig. 3 is a section on the line 3—3 of Fig. 1.

55 Corresponding and like parts are referred to in the following description and designated in all parts of the accompanying drawings by like reference numerals.

Referring to these figures, 2 designates a tubular insulating shell, which may be made of hard rubber, vulcanized fiber, or any other insulating material. The shell is open at both ends. Disposed within the shell, at about its middle, is an interior sleeve 3 of iron or other suitable metal. This shell 3 is tubular in form and has a passage 4 extending through its center, this passage tapering toward one end so as to provide a shoulder 5. Beyond this shoulder the passage is annularly enlarged as at 6, and beyond this enlargement the passage is again 70 annularly enlarged as at 7, thus providing a shoulder 8. Disposed against one end of the sleeve 3, and resting thereon is a magnifying lens 9 which is held in place by a sleeve 10 of metal or any other suitable 75 material. Disposed within the annular space 6 and forced against the shoulder 5 is an annular electrode 11, the central opening of which is eccentric to the exterior diameter. Disposed within the annular enlargement 7 of the bearing or sleeve 3 is a plug 12 of insulating material. This plug is cemented in place within the sleeve 3, and passing through the plug is the screw pin 13, the inner extremity of which carries the 80 electrode pin 14. This pin 14 is disposed eccentrically to the axis of the screw pin 13, so that as the screw pin is turned, the electrode pin 14 may be brought nearer to or farther from the wall of the central opening 85 in the annular electrode 11. The screw pin 13 is provided with a head 15 around which fits a shackle ring 16 having an eye to which is connected a chain 17. This chain may be of any suitable length and is normally contained within a chamber 18 formed by the unoccupied hollow end of the insulating tube 2. The extremity of the chain 17 has attached to it a shackle ring 19 connected with a swivel 20 carrying a ring 21. This 90 swivel is operatively engaged with a metal cap 22 having a diameter approximately equal to that of the tubular body 2 and having an interiorly extending flange 23 fitting snugly within the tube 2, so that when this 95 cap is in place it will be held by frictional engagement with the walls of the insulating tube.

The operation of my invention is as follows: The lens 9 is not only for the purpose 100 of slightly magnifying the spark 11 passing between the electrodes 14 when the device is in use, but also acts to prevent the entrance of dust into the bore 4 and onto the elec-

trodes. It is of course obvious that dust cannot enter through the plug 12, inasmuch as the bore of this plug is always tightly closed by the screw pin 13. In use the cap 22 is removed from the end of the tube and the ring 21 is placed on top of the spark plug. If a spark jumps between the electrodes of the spark plug a small spark will pass between the electrodes 11 and 14 which will be plainly seen through the magnifying glass 9. It will be understood that this tester works with a high voltage current which is obtained through an induction coil, and I have found in practical experience with my tester that when the ring 21 is placed on top of the spark plug a small spark will jump across from electrode 11 to electrode 14 when the primary circuit of the induction coil is broken. Because of the fact that this is used on a secondary circuit with a high tension current, the current will flow into the electrode 11 and the current will jump across the gap to the electrode 14. The magnifying glass 9, it will be noted, is disposed inward of the adjacent end of the insulating tube 2, and the end of this tube is rounded as at 24, thereby permitting the tube to be applied to the eye so that an observer may look into a dark chamber and thus permit the spark to be plainly visible. It will be plain that my device is extremely convenient for use because of the fact that the flexible conductor 17 permits the instrument to be applied to the eye while the contact 21 is held against the spark plug. This eliminates the necessity of holding the implement itself in position against the spark plug and having to cramp the body at considerable personal inconvenience in order to observe the spark. By the use of my device the operator can stand upright and hold the tube 2 in any convenient position to the eye while holding the contact 21 against the spark plug with one hand. It also permits the device to be used where the spark plugs are difficult of access.

Because of the peculiar construction of my tester and the fact that it has no return conductor the spark which will jump between the electrodes will be extremely small and would be very difficult to observe with the naked eye, particularly if the electrodes were not contained in a dark chamber. It is for this reason that it is necessary to provide a tube or casing wherein the electrodes are supported, this casing being opaque, and it is for this reason that it is necessary to provide in my construction a magnifying glass whereby the spark between the electrodes may be observed.

I am aware that spark plug testers have been provided in which one of the electrodes is adapted to be connected by a conductor to a spark plug and the other electrode connected to a ground either through

a return wire or conductor or through the body of the operator, but constructions of this character are open to the objection that inasmuch as a complete circuit is provided the plug will short circuit more or less so 70 that the plug will not give a full spark. A complete circuit using two conductors, as above described will give a fair-sized spark in the spark gap of the tester while a single connection, that is a construction not using 75 a return circuit, gives only a very small spark. In testing spark plugs only one conductor should be used, as in my device, as otherwise the current will be split, part of the current going through the spark plug 80 and the other part through the tester. In my tester I have no short circuit or appreciable return and therefore get the full spark the plug is giving at the time tested. While a very small spark is displayed in the tester, 85 yet by means of the connections stated and by using the magnifying glass this spark is entirely evident to the operator.

My device is extremely convenient for testing spark plugs, but it may also be used 90 in a large number of other situations where it is desired to test the efficiency of secondary circuits.

It will be seen that this tester is very compact, and portable, and that, the parts being 95 contained entirely within the tubular shell 2, are housed and protected from damage or dirt. If the lens 9 should, at any time, become damaged, it may readily be removed.

Having described my invention, what I 100 claim is:

1. A spark plug tester comprising a support of insulating material, coating spaced electrodes carried by the support and insulated thereby and a single conductor connected to a single one of said electrodes. 105

2. In a spark plug tester of the character described, an insulating supporting body, spaced electrodes mounted therein, a flexible metallic conductor attached to one of said 110 electrodes and having means at its end whereby it may be electrically engaged with the spark plug, the other of said electrodes being insulated by said shell.

3. In a spark plug tester of the character 115 described, an insulating shell; a metallic sleeve disposed within the shell, an annular electrode carried by the sleeve, a non-conducting plug disposed in the sleeve, an electrode disposed within the plug and carried 120 in spaced relation to the first named electrode, and a flexible connection connected to said electrode.

4. In a spark plug tester of the character 125 described, a hollow shell of insulating material, a metallic sleeve disposed within the shell intermediate the ends thereof, a lens mounted upon one end of said sleeve, an annular electrode adjacent the other end of the sleeve, an insulating plug disposed in 130

the last named end of the sleeve, an electrode carried thereby and coacting with the first named electrode, a detachable cap closing the last named end of the tubular body, and a chain attached to the last named electrode and to the cap and having a greater length than the distance between the electrode and the cap and normally contained in the hollow body.

10 5. In a spark plug tester of the character described, a tubular body of non-conducting material, a metallic sleeve disposed within the body intermediate its ends, a magnifying lens supported at one end of the sleeve,

15 a coacting electrode supported in the other end of the sleeve in spaced relation to the first named electrode, a cap closing the end of the body opposite the magnifying lens, and a flexible conductor between said last

20 named electrode and said cap, said connection being normally contained within the hollow end of the body.

6. In a spark plug tester of the character described, a tubular body of insulating material, a metallic sleeve disposed within the body intermediate its ends and having a bore tapering toward one end, the bore then being enlarged, a magnifying lens disposed against the end of the sleeve at the large end of the bore, means for holding the lens in place, an annular electrode disposed within the sleeve at the small end of the tapered bore, a plug of insulating material disposed in the enlargement of said bore, a 35 rotatable pin carried in said plug and having an eccentrically disposed electrode pin extending therefrom and coacting with the first named electrode, a cap detachably closing the end of the body opposite the magnifying glass and carrying a member adapted to be applied to a spark plug, and a flexible metallic conductor disposed between said pin and said cap.

7. In a spark plug tester of the character described, an insulating shell, an electrode carried within the shell, an electrode also disposed within the shell and mounted therein in spaced relation to the first named electrode, there being a space between said second named electrode and the adjacent end of the shell, a flexible conductor connected to one of said electrodes and adapted to be disposed in the space between the electrodes and the adjacent end of the shell, 55 said flexible connection having a length greater than the distance between the electrodes and the adjacent end of the shell and a cap detachable from that end of the body through which the flexible conductor is 60 adapted to project.

8. In a spark plug tester, spaced electrodes, one of said electrodes being annular in form, the other of said electrodes com-

prising a pin having an electrode proper disposed thereon and the eccentric to the 65 axis of the pin, the axis of the first electrode being disposed eccentrically to the axis of said pin.

9. In a spark plug tester of the character described, a shell of insulating material, an 70 annular electrode disposed within the shell, a non-conducting plug disposed within the shell, an electrode disposed within the plug and carried in spaced relation to the first named electrode, and means whereby the 75 second named electrode may be connected to a spark plug.

10. In a spark plug tester, a supporting body of insulating material, an electrode disposed within the body and insulated 80 thereby, an electrode also carried by the body coacting with but spaced from the first electrode and means whereby the second named electrode alone may be electrically connected to a spark plug. 85

11. A spark plug tester including a supporting body of insulating material, coacting insulated electrodes carried thereby and spaced from each other, and a single conductor extending from and electrically connected to one of said electrodes alone and adapted to be connected in electrical engagement with a spark plug. 90

12. In a spark plug tester, a supporting body of insulating material, coacting insulated electrodes carried thereby and spaced from each other, an electrical conductor connected to and extending from a single one of said electrodes, the other electrode being entirely insulated from electrical connection with a ground. 95 100

13. In a spark plug tester, a supporting body of insulating material, an electrode carried thereby, means whereby the electrode may be electrically connected to a spark plug and an electrically conductive body carried by the supporting body and insulated thereby from grounding, having a relatively large electrical capacity and coacting with and spaced from said first-named electrode. 105 110

14. A spark plug tester, including a hollow body, coacting insulated spaced electrodes carried therein and a flexible conductor connected to one of said electrodes 115 and having on its extremity a cap adapted to close one end of the hollow body and including a metallic member to which the said conductor is electrically connected.

In testimony whereof I hereunto affix my 120 signature in the presence of two witnesses.
